UNITED STATES PATENT OFFICE

LOUIS MEYER, OF MILFORD, ILLINOIS

DOOR-OPERATING MECHANISM

Application filed November 13, 1926. Serial No. 148,175.

My invention relates to door operating mechanisms, and it is particularly related to a device for opening doors which may be operated at a point remote from the door itself.

In my Patent No. 1,265,229, I have disclosed a door opening mechanism which may be used advantageously in combination with garage doors or the like, where it is desirable 10 that the driver be enabled to operate the door without alighting from the carriage.

The present invention has for its objects the provision of certain improvements over the original embodiment, whereby greater 15 smoothness of operation and simplicity of construction is realized.

More specifically, the objects of my invention reside in improving the operating characteristics of the door interconnecting bar, 20 whereby the doors may be actuated with greater freedom and independence of movement, yet at the same time coaction between said doors is bettered thereby.

Other improvements in the door actuating 25 mechanism have been devised for the purpose of distributing the components of force applied thereto more advantageously, with the view at all times of maintaining the required force as small as possible.

These and other objects will be more apparent and a better understanding of my invention may be had, by referring to the drawings which form a part of the specification in which

35 Fig. 1 is a perspective view of one form which my invention may assume;

Fig. 2 is a plan view illustrating the relation of the element when the doors are in a 40 closed position;

Fig. 3 is likewise a plan view and illustrates the relation of the element when the doors are in an open position;

Fig. 4 is a fragmentary view on a somewhat enlarged scale of a portion of the structure illustrated in Fig. 3.

Fig. 5 is a fragmentary elevational view of the parts illustrated in Fig. 4, and taken substantially on the line V—V of Fig. 3.

50 Fig. 6 is a cross-sectional view through

the connection for illustrating its compressible telescoping characteristics.

In practicing my invention, I provide a vertical frame structure 11, which forms the pivotal supports for two complementary doors 12 and 13. A V-shaped member 14, having its ends bolted to the building structure together with a vertically inclined central member 16 likewise bolted at one end to the building structure 11 and connected 55 at the other end to the apex of the V-shaped member 14, constitute the frame of the door operating mechanism. The frame may be lengthened or otherwise adjusted in order that the same device may be employed with 60 doors of any size.

A vertically disposed pin 17, having a lower bifurcated extremity, is pivotally mounted in the frame at the junction of the V-shaped member and the inclined member. 70 A cross pin 18 is disposed in the bifurcated portion of the vertical member 17, from which is pivoted one link 19 of a dual armed toggle mechanism 21. A plurality of oppositely disposed apertures 22 are provided in the arms of the link 19 for the purpose of accommodating a pin 23 from which one end of a complementary link 24 of the toggle mechanism 21 is pivoted. The other end of the link is forked and is pivotally joined 75 by means of a pin 25 to a vertical bifurcated rod 26 that is rotatably mounted in journal elements 27, which are secured to the door 12. A wire spring 28 is coiled about the pin 25 within the forked portion 80 of the link 24, one end thereof being secured to the link at 29 whereby it will urge the same in a downwardly direction.

A rope or cable 31 is secured to the free end of the dual armed link 19 and is trained over a pulley 32 that is bracketed from the inclined member 16. From this pulley the cable is conducted to an auxiliary pulley 33 that is secured to the wall structure. Obviously it may be conducted in any direction desired where it will be most convenient and serviceable for the operator.

In order that the doors may be opened 95 coactively, a bar mechanism 35 is provided which consists of the relatively short rod 36

that is pivotally secured at one end to the door 12, and adapted to swing in a horizontal plane. A short pin 37 is transversely disposed, and rigidly secured in the pivoted rod 36. A hollow rod 38 which is provided with a slot 39, to receive the pin 37, is pivotally bracketed from the other door and contains a portion of the rod 36. Within the hollow portion thereof, a coiled spring 41 is lodged which urges the rod 36 outwardly, and the transverse pin 37 into engagement with the end of the slot 39. This portion of the machine is likewise of an adjustable construction, and is adapted to be employed with doors of widely different dimensions.

The doors are urged into an open or closed position by means of a spring mechanism 43, that consists essentially of a rotatable pulley 44, having a vertical axis that is mounted upon a bracket member 45, which is bolted to the door. The pulley engages the inner surface of an arcuate member 46 which is pivoted at one end from the wall 11, whereas the other end is interconnected with the wall by means of a coiled spring 47. The configuration of the arcuate member is such that the spring 47 is tensioned most when the door 12 is substantially perpendicular to the wall 11. A slight pivotal movement of the door from this position either in one direction or the other, will enable the spring to relax, thereby either opening the door completely or closing the same.

To open the doors from a closed position requires only that the cord or cable 31 be pulled outwardly, thereby pivoting the links of the toggle member 21 upwardly. Only the door 12 is at first actuated but after the transverse pin 37 engages the end of the slotted portion of the hollow rod 38, the movement becomes coactive and the doors are opened simultaneously. At the same time, the pulley member 44 rides the surface of the pivoted arcuate member, tensioning the spring 47 until the door has turned through an angle of 90°. After it has reached a position slightly beyond 90°, additional movement of the cable is unnecessary in that the spring member 47 will not only complete the pivotal movement of the door 12 by reason of its contracted force, but will simultaneously complete the pivotal movement of the complementary door 13 through the agency of the telescoping bar member 35.

It will be observed that the compressible character of the bar 35 results in a greater freedom and smoothness of operation; furthermore, the extended link of the toggle member not only facilitates the opening operation in that it affords a greater and desirable lever action, but it tends also to lessen the necessary force which must be applied.

While I have described but a single embodiment of the principles of my invention,

and have illustrated but one form which it may assume, it will be apparent to those skilled in the art that they are susceptible to numerable modifications, and I desire therefore, that the invention be limited only to accord with the prior art, in the appended claims.

Having thus described my invention, what I claim and desire to secure by Letters Patent is:

1. The combination with a vertical support having two complementary door members hinged therefrom; of a door operating mechanism comprising a frame relatively stationary with respect to the pivotal door member; two link mechanisms pivotally and rotatably joined to the frame and one of the door members respectively, one link being pivotally joined intermediate the ends of the second link; the free end of said second link extending across the path of movement of said first link; means secured to the free end of the second link for manipulating the links; and means interconnecting the doors for effecting coactive movement therebetween.

2. The combination with a vertical support having two complementary door members hinged therefrom; of a door operating mechanism comprising a frame relatively stationary with respect to the pivotal door members; two link mechanisms pivotally and rotatably joined to the frame and one of the door members respectively; one link being pivotally joined intermediate the ends of the second link; the free end of said second link extending across the path of movement of said first link; means secured to the free end of the second link for manipulating the links; and a resilient member pivotally joined to one of the doors and pivotally bracketed to the other door adapted to effect coactive movement between the doors.

3. The combination with a vertical support having two complementary door members hinged therefrom; of a door operating mechanism comprising a frame relatively stationary with respect to the pivotal door members; two link mechanisms each of which are pivotally and rotatably joined to the frame and one of the door members respectively; one link being pivotally joined intermediate the ends of the second link; means secured to the free end of the second link for manipulating the links; means interconnecting the door for effecting coactive movement therebetween; and a member provided with a cam surface having one end pivotally joined to the support, the other end being resiliently maintained in operative position.

In testimony whereof, I affix my signature.
LOUIS MEYER.
